S. R. CORRELL

COW HOPPLE HOOK FORMER

Filed Nov. 8, 1923

Patented Dec. 30, 1924.

1,521,358

UNITED STATES PATENT OFFICE.

SOLOMON R. CORRELL, OF FERNDALE, WASHINGTON.

COW-HOPPLE-HOOK FORMER.

Application filed November 8, 1923. Serial No. 673,596.

To all whom it may concern:

Be it known that I, SOLOMON R. CORRELL, a citizen of the United States, and a resident of Ferndale, in the county of Whatcom 5 and State of Washington, have invented a new and useful Cow-Hopple-Hook Former, of which the following is a specification.

My invention relates to improvements in cow-hopple hook formers. The cow-hopple 10 hooks which my former is designed to shape are used to prevent cows from kicking while being milked. A pair of these hopples consists of two hooks connected by a chain of 15 adjustable length. Each hook is engaged with the tendon in proximity to and above the hook with the shank of the hook bearing on the outside of the cow's leg. The chain is then adjusted to cause both hook shanks to bear against the cow's legs on the outside 20 thereof. Thus hopped the cow cannot raise one hind leg alone without causing the hooks to twist on the tendons and cause pain and a sense of helplessness. These hopple 25 hooks are made of thin strap iron and hitherto have been shaped with little regard to their properly fitting the leg and their edges frequently have needlessly injured and broken the skin. The object of my improvement is to provide a simple, hand- 30 operable hook former adapted to quickly shape a cow-hopple hook to fit the leg and with outwardly turned edges which can not bear upon the skin.

I attain this object with the device illustrated in the accompanying sheet of drawings, which forms a part of this specification, and in which Figure 1 is a plan view of Fig. 1, Fig. 3 is a front end elevation of Fig. 2, Fig. 4 is a plan view of the eccentric pin with handle attached, Fig. 5 is an end elevation of Fig. 4, Fig. 6 is a side elevation of a hopple hook shaped in my former, and Fig. 7 is a front end elevation of Fig. 6. 45 Similar characters refer to similar parts throughout. Certain parts are broken away for lack of space or to show other parts hidden thereby.

More particularly: A die plate 8 is 50 adapted for mounting in a vise and has two upwardly-projecting ears 9, 9, opposite each other and bored in line to mount pin 11. On pin 11 is mounted for revolution eccentric clamp roller a^{10} provided with handle 55 10. Between ears 9 a hole a^8 is made entirely through plate 8. The front end of

plate 8 is thickened and grooved and rounded at b^8 to serve as a die on which a concave hook can be formed. Transversally through this shaped plate end is made hole 60 c^8 large enough to receive the largest part of an eccentric pin. A handle 12 has a bifurcated shank a^{12} , a^{12} . Transversally through said shank ends is made a hole, in one end as large as the largest part of an eccentric pin, while in the other end only as large as the smaller part of said pin. An eccentric pin has ends 13 and b^{13} of equal diameter and concentric, while its middle part a^{13} is of larger diameter and eccentric 70 with said ends. End b^{13} is longer than end 13 and has threaded end c^{13} adapted to engage a nut 17. On the part of end b^{13} proximate to eccentric body a^{13} is mounted bushing 14 of diameter equal to eccentric 75 body a^{13} . Between bushing 14 and threaded end c^{13} the pin is fitted with key 15, and on this part of end b^{13} is mounted handle 16 engaged with key 15 and retainable in place by nut 17. The end of handle 16 is 80 bent at a^{16} and extends as far over eccentric pin body a^{13} as the middle thereof. Another hole is made through each of shanks a^{12} in line and has an axis parallel with the axis of said holes in said shank ends. In these holes is placed pin 19 on which is mounted 85 for revolution oval shaping roll 18.

In operation: Plate 8 is clamped in a suitable vise, not shown, positioned as illustrated in Figs. 1-3. Handle 10 is placed 90 horizontally to the rear, handle 12 is set vertically above and handle 16 vertically below as shown in full lines in Fig. 2.

A proper blank A for a hook has its front end made red hot and is placed on plate 95 8 with its rear end between ears 9 and as far as the rear edges thereof and its front end between shanks a^{12} , lying on concave end b^8 and extending beyond said plate at the front thereof. Handle 10 is raised to 100 its dotted position at 10' thus forcing eccentric roller a^{10} down on the rear end of the hook blank and firmly clamping the same to plate 8. Then handle 16 is carried forward and upward to its dotted position at 16' 105 which movement revolves the eccentric pin and forces shanks a^{12} to their lowest position in reciprocation at dotted position $a^{12''}$. With said shanks has also moved downward shaping roll 18 and forced blank 110 A to conform to the concave shape of the die immediately below said roll 18. Then

handle 12 is revolved forward and downward and carries along with it handle 16 the bent end a^{16} of which is in its path of movement at $a^{16'}$. Thus as handle 12 is caused to revolve it turns on body a^{13} of the eccentric pin and maintains its concentric relation with the concave and rounded end b^8 of the die. By the time handle 12 has reached its dotted position at $a^{12''}$ shaping roll 18 has moved over the entire periphery of concave and rounded end b^8 and the soft hook blank has been caused to conform to the shape thereof. Then handle 12 is returned to its full-line position, handle 16 is allowed to remain vertically beneath the plate, handle 10 is returned to its full-line position and a tool is inserted from beneath in hole a^8 and caused to bear against the rear end of the hook A while it fulcrums on the rear wall of the hole and forces the newly-formed hook A from engagement with the rounded end b^8 of the die plate. Thus is obtained the shape illustrated in Figs. 6 and 7.

Having thus disclosed my invention, what I claim as new and desire to secure by Letters Patent is,—

1. In a hook former in combination, a die plate having a rounded concave end adapted for a hook die and a transverse hole therethrough concentric with said rounded end, a pin mounted for revolution in said hole having projecting ends eccentric therewith, a handle having a bifurcated shank the ends of which are mounted for revolution on said eccentric pin ends, and a shaping roll mounted for revolution on said shank adapted to traverse said shaped die plate end as said handle is revolved on said pin.

2. In a hook former in combination, a die plate having a rounded concave end adapted for a hook die and a transverse hole therethrough concentric with said rounded end, a pin mounted in said hole for revolution having protruding eccentric ends, a forming handle having a bifurcated shank the ends of which are mounted for revolution on said eccentric pin ends, a shaping roll mounted for revolution on said shank adapted to traverse said shaped die plate end as said handle is revolved on said pin, and a pin handle fixed on one end of said

eccentric pin adapted to revolve said pin in said plate hole and in said shank ends and having a curved end within the path of said forming handle when the same is revolved forward whereby said shaping roll is caused to approach said die plate by revolving said pin handle from a position beneath said die to a position above the same and said shaping roll is caused to traverse said hook die in its nearest approach thereto as said forming handle together with said pin handle are revolved from a position above said die to a position below the same.

3. In a hook former in combination, a die plate having a rounded concave end adapted for a hook die and a transverse hole therethrough concentric with said rounded end, a pin mounted in said hole for revolution having protruding ends eccentric therewith, a forming handle having a bifurcated shank the ends of which are mounted for revolution on said eccentric pin ends, a shaping roll mounted for revolution on said shank adapted to traverse said shaped die plate end as said handle is revolved on said pin, a pin handle fixed on one of said eccentric pin ends adapted to revolve said pin in said die and also in said shank ends and having a curved end within the path of said forming handle when the same is revolved forward, and an eccentric roll mounted for revolution transversely and above the rear end of said die plate having a handle and adapted to clamp the rear end of a hook blank to said die plate, whereby a hook blank having a red-hot front end is placed on said die plate, with its rear end beneath said clamping roll and its front end between said bifurcated shank and protruding in front thereof when said forming handle is in the vertical above said die plate, is clamped to said die plate by revolving said clamping roll and is shaped to conform with said hook form on the front end of said die plate by forcing said shaping roll against said blank by revolving said pin handle from a vertical position beneath said die plate to a vertical position above said plate and then revolving said forming handle and said pin handle together forward to a position beneath said die plate.

SOLOMON R. CORRELL.
